(57) **CLAIM**

The ornamental design for a boiler brush therefor as shown
and described.

DESCRIPTION

FIG. 1 is a left side elevational view of the boiler brush,
showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a front, left perspective view thereof, shown in an
environment of use.

The broken lines shown in FIG. 6 are for the purpose of
depicting environmental subject matter, and form no part of
the claimed design.
